DESK OR SIMILAR ARTICLE

Alexis M. Yermakov, San Francisco, Calif., assignor to Stow & Davis Furniture Company, Grand Rapids,
Mich., a corporation of Michigan

Filed Aug. 29, 1967, Ser. No. 8,413

Term of patent 14 years

(Cl. D33—7)

FIG. 1.

FIG. 2.

FIG. 4.

FIG. 3.

FIG. 1 is a perspective view of a desk or similar article showing my design;

FIG. 2 is a front elevational view of the desk or similar article shown in FIG. 1;

FIG. 3 is a side elevational view of the desk or similar article shown in FIGS. 1 and 2; and

FIG. 4 is a partial top or plan view of the desk or similar article shown in FIGS. 1, 2, and 3.

The dominant features of my design reside in those portions which are shown in full line of the drawings.

I claim:

The ornamental design for a desk or similar article, substantially as shown and described.
